OF PENNSYLVANIA.

PRINTING-BLOCK-CONTROL MECHANISM.

1,263,900.

Specification of Letters Patent. Patented Apr. 23, 1918.

Application filed August 16, 1917. Serial No. 186,455.

To all whom it may concern:

Be it known that we, ALFRED JONES and HARRY A. WEBSTER, both citizens of the United States, and residents of Lancaster, Lancaster county, Pennsylvania, have invented a new and useful Printing-Block-Control Mechanism, of which the following is a full, clear, and exact description, reference being had to the accompanying drawings, forming part of this specification, in which—

Figure 1 is a diagram of one form of the invention in which we have shown the fabric in its passage through the machine, the printing blocks, and the electrically controlled devices therefor.

Fig. 2 is a similar view showing a modified form.

Fig. 3 is another similar view showing another modified form.

Fig. 4 is a side elevation of a portion of a well known block printing machine, to which we have shown our controlling mechanism attached.

Fig. 5 is a face view on a larger scale of a portion of the controlling mechanism.

Fig. 6 is a similar view, partially in section, on a larger scale.

Fig. 7 is a perspective view of the actuating bar guide.

Figs. 8, 9 and 10 are diagrams of the actuating bar slide ratcheting mechanism.

Fig. 11 is a sectional view on the irregular line XI—XI of Fig. 5.

Fig. 12 is a perspective view of the selector switch cam.

Fig. 13 is a perspective view of the actuating pawl releasing lever.

Fig. 14 is a plan view of the retaining pawl.

Fig. 15 is an edge view thereof.

Fig. 16 is a sectional view on the line XVI—XVI of Fig. 17.

Fig. 17 is a sectional view on the line XVII—XVII of Fig. 16.

Fig. 18 is a plan view of the selector switch cam operating lever.

Fig. 19 is an edge view thereof, partially in section.

Fig. 20 is a perspective view of the retainer for the ratcheting mechanism for the actuating bar slide.

Fig. 21 is a perspective view of one of the actuating bars.

Fig. 22 is a side elevation of an actuating bar key.

Fig. 23 is a sectional view of the actuating bar key.

Fig. 24 is an edge view of the actuating bar guard.

Fig. 25 is a plan view of the guard.

Fig. 26 is an edge view of one of the switch levers.

Fig. 27 is a plan view thereof.

Fig. 28 is a plan view of a switch similar to that shown in Fig. 27, but in which the actuating lug has been placed on the other leg thereof.

Fig. 29 is a plan view of a modified form of a selector switch cam-operating lever.

Fig. 30 is a detail sectional view showing the electrically controlled latch-operating mechanism for one of the printing blocks.

Fig. 31 is a detail sectional view taken at right angles to Fig. 30, and

Fig. 32 is a perspective view of a pawl slide block.

This invention relates to controlling devices for fabric-printing machines of the type having a plurality of printing members or a plurality of sets of printing members for printing different designs on the fabric, and in which the controlling mechanism for the printing members is so arranged that the printing members are caused to automatically operate in a prearranged order with relation to each other, and provides means adapted to vary the order of the operation of the printing members without stopping the machine.

An object of our invention is to provide a cheap and efficient controlling mechanism of this character which can readily be applied to machines of this type, and particularly to block-printing machines, for printing rugs of different lengths without stopping the machine.

Another object of our invention is to pro-

vide a device of this character in which the mechanism is set so that rugs of a predetermined length are printed successively, each having a field and a surrounding border portion. These rugs comprise end sections consisting of borders extending the full width and a plurality of intermediate sections consisting of a body and side borders. Assuming that the machine has been set for printing rugs nine feet long, and there should be a bad spot on the fabric to be printed, if the order could not be changed, one entire rug, and perhaps two entire rugs, would be damaged. By our invention we are enabled to print a rug of different length than that on the run which we are making, so as to bring the bad spot at the end of a rug, and then start a new rug immediately beyond the bad spot, so that only the section of fabric in which the bad spot appears will be wasted. In other words, if we were printing rugs nine feet in length and a bad spot should appear on the end border section of the rug being printed, we can throw the end border printing blocks into operation one section in advance, so that the rug printed will be seven and one-half feet long, and then throw in another border section immediately beyond the bad spot which will form the end border of the next rug.

In the specific form of printing machine and controlling mechanism shown and described, we obtain this object by providing an electromagnetically controlled latch for each printing block, and in which the circuits for the magnets are closed by means of switches which are actuated by selectors. The switches are arranged in groups about a rotatable drum, and each switch is provided with a movable member having one or more actuating lugs lying adjacent to the drum, the actuating lug or lugs of the different groups lying in different planes. If the end borders of the rugs are only one-half the width of the printing blocks, the switches are arranged in two groups, one group controlling the end border blocks, and the other group controlling the field and side border blocks. If, however, the border on the rugs is as wide as one of the printing blocks, the switches will be arranged in three groups, namely, a group for the starting of the border, a group for the finishing of the border, and a group for the field and side border sections.

The drum adjacent to the lugs of the switches is arranged to be rotated in timed relation to the fabric passing through the machine, and the selectors are each provided with an actuating lug for actuating the switches while passing the lugs connected to the movable switch members. The selectors are slidably mounted on the drum and are arranged to move transversely

thereon, in order to permit the lugs on the selectors to be shifted laterally into the path of the lugs on the different groups of switches.

Surrounding the drum are circular guides or selector grooves in which the lugs on the selectors move in a prearranged order to actuate the switches of the various groups whose lugs lie in their path of travel or in the same vertical planes.

In this type of machine, the printing blocks are spaced apart so that during one fall of the blocks, alternate sections of the fabric are in position to receive impressions, and at the next fall of the blocks the other alternate sections are in position to receive impressions, and will be printed upon by the blocks which are over sections which are to receive impressions by the blocks. The machine shown in the drawings is provided with ten printing blocks and twenty five selectors, so that each selector moves in unison with a section of the fabric during its passage through the machine, and actuates the switches in its path to close the circuit through the electromagnets and prevent the printing block controlled thereby from making an impression on the section of the fabric controlled thereby when under said block.

As above stated, the printing on each section of the fabric during its passage through the machine is governed by a selector, and after a given section has passed beyond the last printing block, said selector will have made a complete cycle of switch mechanism and is available for governing the work on another section of the fabric passing into the machine.

The precise nature of our invention will be best understood by reference to the accompanying drawing, which will now be described, it being premised, however, that various changes may be made in the details of construction and general arrangement of the parts, without departing from the spirit and scope of our invention as defined in the appended claims.

In Fig. 1 of the drawings, the reference character 2 designates the fabric passing through the machine, and which, for the sake of clearness, we have divided into sections 2^a, 2^b, 2^c, 2^d, 2^e, 2^f, 2^g, 2^h, 2ⁱ, 2^k, 2^l, 2^m, 2ⁿ, 2^o, 2^p, 2^q, 2^r, 2^s, 2^t, 3^a, 3^b, 3^c, 3^d, and 3^e, designate the printing blocks. In the first group, 3^a are the blocks for printing the end border sections, such as 2^e, 2^h, 2ⁿ and 2^t, while the blocks 3^b form the second group which are for printing the field and side border sections between the above mentioned border sections. The blocks 3^c are idle blocks and are not used for printing a design such as shown in Fig. 1. 4^a, 4^b, 4^c, 4^d, and 4^e are the solenoids for actuating

- the electric switches for controlling the printing blocks of the different groups. Each of these solenoids has a core 5, which is connected to a latch lever 7, for actuating a latch 8 for retaining the printing blocks in their elevated positions and prevent them from moving downwardly to make an impression on the sections of fabric below them. The circuit through each of the magnets is closed by means of a switch having switch-blades 9, a movable switch member 10, having a knife 11, connected thereto, each knife being arranged to enter between its blades 9 to close the circuit through one of the solenoids 4. Each of these switch members 10 is provided with a lug 12, which is arranged to be engaged by a lug on a selector, as hereinafter described, to close the circuit through the switch. One pole of each of the solenoids is connected to a line 13, leading from a source of energy 14; the other line 15 from the source of energy 14 is connected directly to one of the blades 9 of each of the switches. The other blade 9 of each of the switches is connected to the other pole of its solenoid, so that when the knife of the switch engages the blades thereof, the circuit through its solenoid will be closed, which will, in turn, actuate the latch and retain the block controlled thereby in its elevated position.
- 16 designates a drum which, in Fig. 1, has been spread out in a plane, and which is provided with twenty transverse grooves for the reception of selectors 17^a, 17^b, 17^c, 17^d, 17^e, 17^f, 17^g, 17^h, 17ⁱ, 17^j, 17^k, 17^l, 17^m, 17ⁿ, 17^o, 17^p, 17^q, 17^r, 17^s, 17^t, each selector being arranged to control the switches for its particular section of fabric. These selectors are each provided with a projection 18, which is arranged to pass at one side or the other of a dividing plate 19 and to be shifted from one position to another position by means of a switch cam 20, which is located over the selector 17^a in the position shown in Fig. 1, so that the projection on this selector will be shifted to the lower side of the division plate 19, for the purpose hereinafter described.
- 50 In Fig. 1, the printing blocks 3^a, 3^a are arranged to print the end border sections, while the printing blocks 3^b print the field and side border sections between the border sections which forms the ends of the rugs; the blocks 3^c being normally held out of action by the hand latches 21. The projections 12 on the movable switch members 10 for the solenoids 4^a are placed in the space above the division plate 19, so that they will be engaged and all of the switches closed when a selector is shifted so that its projection is above the division plate; while the projections 12 on the switches for the group of solenoids 4^b are below the division plate, so that their switches will be closed 65 by projections on the selectors below the division plate. As the last two printing blocks are not used when printing a design such as shown in Fig. 2, the movable switch members therefore are removed, so that the circuit through the solenoids will not be closed, as the blocks are held out of action by means of the hand latches.
- The machine as set up in Fig. 1 is designed to print rugs in which the border sections have red, blue and black blocks, while the field sections have green and brown blocks, and the side border sections have red, blue and black blocks to conform to the transverse border sections. The red 80 blocks of the border sections are printed by the first block 3^a (which is marked "Red") as shown on section 2^c, and after this section has passed beyond the third printing block 3^a (marked "Black") the end border 85 section will be completed, as shown in the section 2^b. As this section has now been completed, none of the remaining blocks will make an impression thereon. The field and side border sections while passing under the 90 group of printing blocks 3^b will not receive any impression, but the border portions thereof will be printed when passing under the first three blocks 3^b (which are marked "Red", "Blue" and "Black") so that the border portions on these sections will be printed when they have reached the position of the section 2^a. The brown and green blocks in the field sections will be printed by the last two printing blocks in the group 3^b, so that all 100 of the sections will be completely printed when they reach the position of the section 2^a. The machine when set up to print rugs, such as shown in this figure, is arranged to shift the switch cam 20 from its upper position to the position shown in the drawing every sixth step movement of the fabric, so as to print rugs having five field and side border sections, as shown at the left end of the fabric passing through the machine. If 105 a section should have a bad spot such as shown at X in section 2^b the switch cam 20 is shifted one step earlier so as to shift one of the selectors, which, in this case, has been selector 17^e, to the lower position, so that 115 the blocks 3^a will be permitted to descend on the section 2^c, when it is successively brought under these blocks, while the blocks 3^b will be held in their elevated positions when this section is brought under them. 120 This is accomplished by closing the switches for the solenoids 4^b to actuate the latches successively for the switches for the various blocks 3^b when the section 2^c passes under them, so that this rug between sections 2^c 125 and 2^b will have only four field sections. In this construction, the section 2^b will receive impressions from the various field

blocks, as its selector is in the upper groove, but in order to start a new rug, the selector 17^a has been shifted to the lower groove, so that the section 2^a will receive impressions 5 from the end border blocks in succession as it passes under them, while the field and side border blocks 3^b will be held out of action in succession while the section 2^a of the fabric passes under them, as the projection 10 18 of the selector 17^a will close each of the switches for the solenoids 4^b.

It will therefore be readily understood that if it had been necessary to print this rug with five field sections, two rugs would 15 have damaged spots therein, while by our invention, the rug within sections 2^a and 2^b will be slightly shorter than the other rugs without any imperfections, and therefore, the only loss will be one-half of section 2^a, 20 section 2^b, and a half of section 2^c. If this damaged spot should only extend as far as the damaged spot Y on section 2^b, the border blocks could be thrown into action to print on this section, so that only one section 25 would be lost, namely, half of sections 2^b and 2^c.

In Fig. 1, the machine is in such a position that the blocks are ready to descend, and those that are latched will be held in 30 their elevated positions, while those that are free to descend will impress the fabric as indicated in dotted lines on the sections below the blocks. Therefore, sections 2ⁱ, 2^j, 2^p will be printed upon, the impressions being 35 made by these blocks being shown in dotted lines.

In the foregoing description, we have described how the mechanism is set up for printing rugs having three colors in the border and two other colors in the field. It will 40 be understood, however, that the machine can readily be set up for printing different designs and different colors, but in all cases the projections 12 for actuating the movable switch members for the end border blocks will be placed above the division plate, while 45 those for actuating the movable switch members for the switches for controlling the field and side border sections will be placed below the division plate. Therefore, it is only necessary to place the selectors for the end border sections below the division plate and those for the field and side border sections above the division plate by means of the 50 cam 20. This cam 20 is normally in the position to shift all of the selectors above the division plate, and is only shifted when it is desired to print an end border section and is then returned to its normal position.

55 In the machine shown in Figs. 4 to 30, the printing blocks 3, which are of the usual character, are mounted on slide members 22, which are arranged to move between guides 23, and are provided with rollers 24, which

are engaged by cams 25, to raise the blocks 65 to their elevated positions during each step movement of the fabric, to permit the paint pans 26 to pass beneath them to ink the blocks by means of the usual rollers. These paint pans are all connected together by 70 means of links 27, in the usual manner, and are adapted to be moved back and forth by mechanism well known to those familiar with the art during the time that the fabric is fed forward by the belts A. The cams 25 75 for elevating the printing blocks are mounted on shafts 27, there being a cam on each end of said shaft for actuating its printing block. These shafts are rotated in the usual manner. 80 30 is a casing which is located on the side of the printing machine at the operator's stand, and which casing incloses the switch mechanism for the solenoids. Rotatably mounted in bearings in this casing is the vertical shaft 31, which is provided with 85 a worm 31^a, which meshes with a worm wheel 32, on a horizontal shaft 33. This shaft 31 is provided with a bevel gear 34 at its lower end which meshes with a similar bevel gear 35 on a transverse shaft 36, which 90 is driven by means of a bevel gear 37, which meshes with the bevel gear 38 on a shaft 29. This shaft 29 is connected to the shaft 27 by means of beveled gears 28, so that the shaft 95 33 will be rotated in unison with the shafts 27, which actuate the printing blocks; and as all the devices for actuating the switches, as hereinafter described, are operated by the shaft 31, it will be readily understood that all the parts will be in timed relation with 100 the printing machine.

Connected to one end of the shaft 33 and within the casing 30 is the selector drum 16, which is provided with a plurality of transverse grooves 40, for the selectors 17^a to 17^t. 105 Surrounding the selector drum 16 is an annular casing 41, in which is mounted the division plate 19, there being an annular groove on each side of the division plate in which the lugs or projections 18 of the selectors travel. Mounted on the exterior of this annular casing 41 are the stationary switch blades 9, and mounted on pins 42 are the movable switch members 10, having the switch knives 11 at one end and actuating 110 projections 12 at the other end. The actuating projections on the switches for controlling the circuit to the solenoids for the latches for the field and side border blocks extend on one side of the division plate, 120 while the projections on the switches for controlling the circuit to the solenoids for the latches for the end border sections extend into the groove on the other side of the division plate. The gearing for rotating the 125 drum 16 being proportioned so that a selector will move from one position to the next in each step movement of the fabric and will

make a complete revolution in twenty steps, or from the time that a section of fabric passes from the position 2^a of Fig. 1 to the next position beyond 2^a.

5 Slidably mounted in a groove in the casing 41 between the ends of the division plate 19 is a bar 43, which carries the switch cam 20. This bar extends laterally from the drum and is provided with a roller 44 at the other end thereof. This roller 44 rests in a cam groove 45, formed in the end of a lever 46, the other end of the lever having a finger 47, which is arranged to be engaged by an actuating member to shift said lever from the full line position shown in Fig. 11 to the dotted line position. When the switch cam is in the dotted line position, it will shift the next selector passing this point into the groove containing the projections on the ends of the movable members of the switches for closing the circuit to the solenoids to lock the blocks for printing the field and side border sections. Movable mounted on adjustable guides 48, secured to the frame 39 is 20 a slide 49, having ratchet teeth 50. 51 is a spring-actuated pawl connected to a slide block 51^a, actuated by a pitman 52, which is connected to a crank pin 53, on the end of the shaft 31, so that the slide 49 will be advanced the distance of one tooth for each revolution of the shaft 31, and for each movement of the fabric under the printing blocks.

30 Pivottally connected at 54 to the frame 39 is a retaining pawl 55, for retaining the slide 49 in the position to which it has been shifted by the pawl 51. Pivottally mounted on the same pin on which the pawl 55 is mounted is a releasing lever 56, which is normally held in its inactive position (that shown in Fig. 11) by means of a spring 57, there being a similar spring under this spring 57 for retaining the pawl 55 in engagement with the ratchet teeth 50. This 40 pawl releasing lever 56 is provided with a downwardly extending projection 58 which lies in the path of the retaining pawl 55, and also in the path of a retainer 58^a which also lies in the path of the finger 47 on the 45 lever 46.

55 The slide 49 is provided with a cylinder 59 having a piston 60 therein which is connected to one end of a piston rod 61. This piston rod 61 is fixedly connected to a projection on the frame 39, so that the cylinder 59 is adapted to slide over the rod. Surrounding the piston rod 61 and within the cylinder is a coiled spring 62, which engages one end of the cylinder and the piston 60 for moving the slide to the left when the pawls are released, and also for retaining the slide against the actuating pawl 51 or the retaining pawl 55. 63 is a cock in the end of the cylinder 59 for controlling the

65 exhaust of the air from the cylinder and thereby controlling the speed of the return movement of the slide.

Connected to the slide 49 is an actuating bar guide 64, having a plurality of recesses 65 which form guides for the actuating bars 70 65, and which are arranged to be raised and lowered into and out of the path of the end of the finger 47 on the lever 46 by means of keys 66. Each of the actuating bars 65 is provided with a pin 67 which 75 is seated in a recess 68 in its key 66. These keys 66 are pivotally mounted on the shaft 69 on the slide 49, the arrangement being such that when the keys are thrown to the position shown in Fig. 17 the actuating bars 80 will be in their elevated positions, but when either of the keys is moved to the right a distance of approximately ninety degrees the actuating bars will be thrown to their lower positions, as shown at 65^a in Fig. 6, 85 so that the bar which has been thrown to this position will be in the path of the finger 47. Each of the actuating bars 65 is also provided with a locking projection 70 which is arranged to pass over a guard 71 90 when the bars are in their raised positions, and to pass under said guard when in their lowered positions. This guard is connected to the end of a bracket 72 which is secured to the frame 39 and is provided with an 95 opening for the reception of the pivot pin for the lever 46. This guard is placed immediately above the end of the finger 47, so that the operator cannot actuate a key 66 when its bar is in a position to engage the 100 finger 47.

105 The retainer 58^a above described is connected to a slide 73 which is movably mounted in the frame 39, and is arranged to be shifted in one direction by the finger 47 and in the reverse direction by a projection 74 connected to the slide-cylinder 59.

110 In the operation of the machine the drum 16 is continuously rotated in timed relation to the movement of the fabric under the printing blocks, and as the switch cam 20 normally occupies the position shown in Fig. 11 the selectors will pass into the groove in which the projections on the switches for closing the circuits to the magnets controlling the end border latches extend. The actuating bar 65 for making the proper length rug is thrown downward as indicated at 65^a in Fig. 6, and the slide 49 is advanced one step in each movement of the 115 machine. When this bar is moved to the position shown in Fig. 8, it will be in engagement with the end of the finger 47, and on the next movement it will shift the finger to the position shown in Fig. 9, which 120 will in turn shift the switch cam 20 half way to the dotted line position shown in Fig. 11 in order to pass one of the selectors

into the other groove, to print an end border section. On the next advance of the pawl 51 the finger 47 will be advanced to the position shown in dotted lines in Fig. 11 5 and full lines in Fig. 10, which will shift the retainer 58^a to a point where it will pass the end of the projection 58 on the pawl releasing lever 56, which will throw the retaining pawl 55 out of action and also 10 throw the end of the releasing lever into the path of the heel of the pawl 51, so that shortly after this pawl is advanced beyond the position shown in Fig. 10 it will be thrown out of engagement with the teeth 15 50 with which it is now engaged, and assume the dotted line position when it has completed its full throw. The slide is now free to return to its starting point, as both pawls have been disengaged from the ratchet 20 teeth. Just before the slide reaches its starting point, the projection 74 on the slide will engage the retainer 58^a and shift it from the position shown in Fig. 10 to that shown in Fig. 8, which will again permit 25 the pawls to become active to shift the slide 49 to the right. If it is desired to make a rug shorter than that set for the regular run, it is only necessary to throw down an actuating bar 65 in advance of that shown 30 at 65^x in Fig. 6, and after the short length has been completed to cut out a bad spot, this bar is raised to permit the machine to make the regular length rugs.

In Fig. 1 we have shown a compound 35 latch lever 7 and 8 connected by means of a spring for retaining the printing blocks in their elevated positions. This showing is merely diagrammatic, the actual arrangement being shown in Figs. 4, 30 and 31. In 40 these figures there is a through shaft 75 journaled in the frame of the printing machine, there being one such shaft for each printing block, and connected to the end of this shaft is a latch lever 76. Connected to 45 the intermediate portion of the shaft 75 is a lever 77 which is connected to a link 78 slidably mounted on a connecting rod 79. This connecting rod 79 is connected to a core 80 of a solenoid 81 supported on the frame of 50 the printing machine. Surrounding the connecting rod 79 and engaging a washer or nut 82 on the end of the rod 79 and a boss 83 on the link 78 is a coiled spring 84. The arrangement is such that when the solenoid 81 55 is energized the core 80 will be moved downwardly against the action of the spring 84 even though the latch member 76 would be in engagement with the plane surface of a latch lug 85 on the slide 22 during its upward movement. As soon as this lug 85 60 passes the latch 76 the spring 84 will expand and throw the latch into position under the lug 85 to prevent its printing block from falling after the high spot of cam 25 passes

beyond the roller 24. In order to release the 65 latch after the circuit has been broken we connect a weighted lever 86 to the shaft 75, which will move the latch 76 from under the projection 85 when the circuit to the solenoid has been broken.

70 In Fig. 1 we have shown an auxiliary latch 21 for locking the idle blocks out of action, but it will readily be understood that the latches 76 may be moved into position to retain the blocks in their elevated position 75 and locked there by any suitable means.

In the foregoing description we have described a machine for making rugs in which the end border sections are cut along the center, so that one-half of each end border 80 section forms one end of a rug, or in other words, the width of the border on each rug is only one-half of the width of the printing blocks. If it is desired to make rugs having borders of a width equal to the width of a 85 printing block, it will be necessary to cut two sets of printing blocks for printing the end borders, and one set of blocks for printing the field and side border. The one set of border blocks will print the beginning of 90 the rug while the other set will print the ending of the rug.

In Fig. 2, we have diagrammatically illustrated such a machine, in which the two printing blocks 3^b are adapted to print the 95 border at the beginning of the rug, the blocks 3^e the border at the end of the rug, and the blocks 3^f print the field and side border. The four blocks 3^c are idle blocks and are not used for printing a rug such as 100 shown in this figure, which only has two colors. In an arrangement of this character, it is necessary to have three grooves surrounding the drum 16 for the switches, and when a selector projection is in the lower 105 groove the border printing blocks for the beginning of the rug are permitted to fall upon a section, when a selector projection is in the central groove the border blocks for printing the end of the rug are permitted to 110 fall, and when in the upper groove the blocks for printing the field and side border are permitted to fall.

The actuating mechanism for the lever 46 for shifting the switch cam will be similar to 115 that for actuating the lever shown in Fig. 11, with the exception that the finger 47 will be advanced one step from that shown in Fig. 11, whereby the cam 45^a on the end of the lever 46 will be advanced an additional 120 step to that shown in the other figures of the drawings. The normal position for the cam is that shown in full lines, and when the finger is moved to the first dotted line position the switch cam 20 will be shifted to the 125 central groove to finish a rug, when moved to the second dotted line position the switch cam 20 will be moved to the lower groove to

start a rug, and when moved to the third dotted line position the slide will be released. If there should be a bad spot and it is desired to retain the switch cam 20 in front of the lower groove for several movements of the machine in order to throw several selectors in the lower groove to print several beginning sections of the border, the one to be printed over a bad spot and the next to print the beginning section of the border for the next rug, the lever 46 can be held in its full thrown position by hand. This will hold the ratchet mechanism out of action and prevent the slide 49 from returning to its starting point, or if desired the slide itself may be held in this position.

In this figure each of the switch members is provided with two projections 12, so that a selector in either groove will operate two sets of switches, or, in other words, if a selector is in the upper groove it will close the switches for printing both end border sections, if in the central groove it will close the switches for controlling the field blocks and the blocks for beginning a rug, and if in the lower groove it will close the switches for the field blocks and the blocks for printing the end of the rug.

It is sometimes desirable to prevent all of the blocks from descending on one or more sections of the fabric passing through the machine, which may be when there is a bad spot in the fabric, or when a new roll of fabric has been clamped to the end of a roll just passing through the machine. We accomplish this in the manner shown in Fig. 3, in which the machine is set up for printing a rug in two colors, whose border is only one-half the width of the printing blocks, such as shown in Fig. 1. In this figure, we have also shown three grooves for the switch and selector projections, and provided each of the switch members with two projections. The central and upper grooves are precisely the same as those shown in Fig. 1, and the upper projections on the switches are located in the same position as those in Fig. 1. Each of the switch members 10 is provided with an additional projection in the lower groove, the arrangement being such that if a selector is shifted so that its projection passes in the lower groove, such as 17^a, this projection will actuate each of the switches in succession as it passes the projections thereon, and thereby successively lock each printing block and prevent any of them from making an impression on the section of fabric represented by this selector. The lever 46 in a construction of this character is provided with a cam precisely the same as the cam 45 of Fig. 11, with the exception that it is provided with an additional step 45^b at the end thereof, as shown in Fig. 29, and when

it is desired to throw a selector in the lower groove after printing a border section to avoid printing on a bad spot or prevent the printing blocks from descending on the clamp which secures the ends of two rolls of fabric to each other, the lever 46 is pushed to its extreme position by hand immediately after a selector for printing an end border section has been thrown into the end border groove. The lever 46 is held in this position until after the desired number of sections which are not to be printed have passed into the machine, and it is then permitted to move back a sufficient distance to throw a selector into the central or end border groove, and then released to permit the machine to operate to print rugs of the predetermined length.

The advantages of our invention will be apparent to those skilled in the art, since it provides a multiple printing member printing machine by means of which, by the simple control of selector mechanism, the length of the rug or other design can be readily changed, thereby enabling the loss by waste to be reduced to a minimum, as well as enabling the ready changing for any purpose in the length of the design being printed. The invention is particularly advantageous in connection with multi-color design printing, since it enables the various printing members necessary in this work to be readily and easily controlled. The selector mechanism itself is simple in its construction, arrangement and operation and capable of being readily operated. By providing a controlling device, or selector, for each section of the fabric which is at any given time under the operation of the machine, we are able to simultaneously work upon a plurality of different sections and yet perfectly control the operation of the printing members on each section to vary the length of the design being printed as may be necessary with the different conditions of operation as they arise.

It will, of course, be understood that the particular machine which is herein shown and described is illustrative only, and that our invention as set forth in our broader claims is capable of various and widely different embodiments with respect to the character and arrangement of the design-forming members, either by printing or other means; with respect to the locking mechanism for controlling the operation of the printing members, and with respect to the particular character and arrangement of the selector mechanism and their controlling devices.

We claim:

1. In a machine for printing designs on fabrics, printing members of two different types for printing on different portions of

the fabric, means whereby said members are operated in a predetermined order; said means being shiftable during the operation of the machine to change the order of operation of the printing members and a shiftable controlling device for said means for varying the order of the printing, substantially as described.

2. A printing machine having sets of printing members of different types, selectors for controlling said members, and means for shifting said selectors while the machine is in motion to prevent either or both sets of printing members from moving into printing relation, substantially as described.

3. A printing machine having a plurality of printing blocks of different types arranged to be raised and then lowered into printing contact with the material to be printed, means for raising said blocks, selectors for controlling the falling of said blocks, and means for shifting said selectors, said means being arranged to vary the order of the falling of the blocks while the machine is in operation, or to prevent the falling of all of said blocks, substantially as described.

4. A rug printing machine having a field section printing member, a border section printing member, fabric feeding mechanism, means for moving the printing members into and out of printing contact with the fabric, retainers for preventing the printing members from moving into printing contact with the fabric, a shiftable controlling device for each section of the fabric passing the printing members, each controlling member being arranged to actuate one or both of the retainers to prevent a printing member from moving into printing contact with a section of fabric corresponding thereto, and means to move the controlling members in timed relation to the fabric, substantially as described.

5. A rug printing machine having a field section printing member, a border section printing member, fabric feeding devices, means for moving the printing members into and out of printing contact with the fabric, retainers for preventing the printing members from moving into contact with the fabric, a selector for each section of the fabric passing the printing members, each of said selectors being arranged to actuate one of the retainers to hold out the field printing member when a border section is in printing relation thereto, or to hold out the border printing member when a field section is in printing relation thereto or to hold out both printing members when a section is not to be printed on, substantially as described.

6. A rug printing machine having a field section printing member, a border section printing member, fabric feeding devices,

means for moving the printing members into and out of printing contact with the fabric, retainers for preventing the printing members from moving into contact with the fabric, a selector for each section of the fabric passing the printing members, each of said selectors being arranged to actuate one of the retainers to hold out the field printing member when a border section is in printing relation thereto, or to hold out the border printing member when a field section is in printing relation thereto, a selector controlling device for shifting said selectors at a predetermined time and order, and means to shift the selector controlling device to vary the order, substantially as described.

7. A rug printing machine having a field section printing member, a border section printing member, fabric feeding devices, means for moving the printing members into and out of printing contact with the fabric, retainers for preventing the printing members from moving into contact with the fabric, a selector for each section of the fabric passing the printing members, each of said selectors being arranged to actuate one of the retainers to hold out the field printing member when a border section is in printing relation thereto, or to hold out the border printing member when a field section is in printing relation thereto, a selector controlling device for shifting said selectors at a predetermined time and order, and means to shift the selector controlling device to vary the order, substantially as described.

8. A rug printing machine having a field section printing member, a border section printing member, fabric feeding devices, means for moving the printing members into and out of printing contact with the fabric, retainers for preventing the printing members from moving into contact with the fabric, a selector for each section of the fabric passing the printing members, each of said selectors being arranged to actuate one of the retainers to hold out the field printing member when a border section is in printing relation thereto, or to hold out the border printing member when a field section is in printing relation thereto, a selector controlling device for shifting said selectors at a predetermined time and order, and means to shift the selector controlling device to vary the order, substantially as described.

9. Controlling mechanism for printing machines, comprising selectors for controlling the printing operation of the printing members, each of said selectors representing a portion of the part to be printed, a selector controlling device for shifting said selectors at a predetermined time and order, and means to shift the selector controlling device to vary the order, substantially as described.

10. In a printing machine having a plurality of printing members, electrically con-

trolled latches for said printing members for retaining them in inactive positions, and a selector for each portion of the part to be printed for actuating the electrical devices for the switches, and means for shifting said selectors during the operation of the machine, substantially as described.

11. A controlling device for printing members of a printing machine, comprising a movable member having a plurality of selectors mounted thereon, and means for shifting said selectors in a pre-arranged order, said means being adapted to be shifted during the operation of the machine to vary the order thereof, substantially as described.

12. A controlling device for electrically actuated latches for printing blocks of a printing machine, comprising a drum, electrical switches mounted about said drum, movable selectors on the drum for actuating the switches, and means for shifting said selectors to vary the order of actuation of the switches, substantially as described.

13. A block printing machine for printing rugs, comprising movable blocks, said blocks being arranged in groups for printing the border sections and field sections, electrically controlled latches for retaining the blocks in their inactive positions, a rotary drum, electrical switches arranged in groups about said drum for controlling the latches, movable selectors mounted on the drum and arranged to actuate the switches, and means for shifting said selectors in a pre-arranged order, substantially as described.

14. A block printing machine for printing rugs, comprising movable blocks, said blocks being arranged in groups for printing the border sections and field sections, electrically controlled latches for retaining the blocks in their inactive positions, a rotary drum, electrical switches arranged in groups about said drum for controlling the latches, movable selectors mounted on the drum and arranged to actuate the switches, and means for shifting said selectors in a prearranged order, said means being adapted to be varied while the machine is in motion to change the order of the selectors, substantially as described.

15. A controller for printing members of a printing machine, comprising an automatic controlling device for each printing member in use, a plurality of selectors for actuating the controlling devices, means for relatively moving the selectors and controlling devices, and means for relatively shifting the selectors and controlling devices in a pre-arranged order, such means being arranged to be shifted during the operation of the machine to vary the order thereof, substantially as described.

16. A controller for printing members of

a printing machine, comprising an automatic controlling device for each printing member in use, a movable support, a plurality of selectors for actuating the controlling devices slidably mounted on such support, means for moving the support relative to the controlling devices, and means for shifting the selectors in the movable support in a pre-arranged order, such means being arranged to be shifted during the operation of the machine to vary the order thereof, substantially as described.

17. A controller for printing members of a printing machine, comprising an electrical controlling device for each printing member in use and a rotatable support, a plurality of selectors, for actuating the electrical controlling devices slidably mounted in said drum, means for shifting the selectors in the drum in a pre-arranged order, such means being arranged to be shifted during the operation of the machine to vary the order thereof, substantially as described.

18. A controlling device for printing members of a printing machine, comprising a rotatable drum having a plurality of selectors slidably mounted thereon, and means for shifting said selectors on the drum in a pre-arranged order, said means being adapted to be shifted during the operation of the machine to vary the order thereof, substantially as described.

19. A controlling device for printing members of a printing machine, comprising a continuously movable member having a plurality of shiftable selectors thereon, controlling means for the printing members arranged to be actuated by the selectors, and a switch cam for shifting said selectors on the continuously movable member, substantially as described.

20. A controlling device for printing members of a printing machine, comprising a rotatable drum, a plurality of shiftable selectors thereon, controlling devices for the printing members arranged to be actuated by the selectors, and means for shifting said selectors on the drum in a pre-arranged order, said means being adapted to be shifted during the operation of the machine to vary the order thereof, substantially as described.

21. A controlling device for printing members of a printing machine, comprising a rotary drum, a plurality of selectors slidably mounted on said drum, said selectors having actuating members thereon, a shift cam for shifting the selectors, and means for shifting said shift cam at predetermined intervals to move the selectors in a pre-arranged order, said cam being adapted to be shifted during the operation of the machine to vary the order of the selectors, substantially as described.

22. A controlling device for printing members of a printing machine, comprising a

rotary drum, a support surrounding said drum, a plurality of sets of electrical switches connected to said support and surrounding the drum, a plurality of movable 5 selectors mounted on the drum, said selectors being arranged to be shifted to actuate either set of switches, a shift cam to move the selectors in a pre-arranged order, said cam also being adapted to be shifted during 10 the operation of the machine to vary the order thereof, substantially as described.

23. A controlling device for printing members of a printing machine, comprising a rotary drum, selectors shiftably mounted on 15 said drum, a support surrounding said drum, a plurality of sets of electrical switches on said support arranged to be actuated by the selectors, a switch cam for shifting the selectors to either one or the 20 other set of said switches, means for actuating the switch cam to shift said selectors in a pre-arranged order, the switch cam also being arranged to be moved to a position to shift a selector or selectors to actuate 25 both sets of switches, substantially as described.

24. A controlling device for printing members of a printing machine, comprising a rotatable drum, a plurality of shiftable 30 selectors thereon, controlling devices for the printing members arranged to be actuated by the selectors, a switch cam for shifting the selectors in a pre-arranged order, and an actuating device for said switch cam arranged 35 to periodically move the switch cam, said means being arranged to be changed during the operation of the machine to vary the order of the movement of the switch cam, substantially as described.

40 25. A controlling device for printing members of a printing machine, comprising a movable member, a plurality of shiftable selectors thereon, controlling devices for the printing members arranged to be actuated 45 by the selectors, a switch cam for shifting the selectors, a reciprocating slide, actuating bars carried by the slide arranged to shift the switch cam, means for raising and lowering the bars into actuating position with 50 relation to the switch cam, means for moving the slide forward step by step, and means to return the slide to its initial position after the cam has been shifted, substantially as described.

55 26. A controlling device for printing members of a printing machine, comprising a movable member, a plurality of shiftable selectors thereon, controlling devices for the printing members arranged to be actuated 60 by the selectors, a switch cam for shifting the selectors, a reciprocating slide, actuating bars carried by the slide arranged to shift the switch cam, means for raising and lowering the bars into actuating position with 65 relation to the switch cam, means for mov-

ing the slide forward step by step, means to return the slide to its initial position after the cam has been shifted, and means to return the cam to its initial position, substantially as described.

70 27. A selector switch cam actuating mechanism for printing members of a printing machine, comprising a reciprocating slide, a pawl and ratchet mechanism for moving the slide in one direction, a holding pawl 75 for holding the slide in its shifted position, movable actuating bars connected to said slide and arranged to be moved into operative position with relation to the switch cam, a releasing device for the holding pawl, arranged to be actuated by the switch cam, and means to return the slide after the holding pawl has been released, substantially as described.

80 28. A selector switch cam operating device 85 for printing members of a printing machine, comprising a reciprocating slide, ratchet teeth on said slide, a pawl, means for moving said pawl step by step to advance the slide, a holding pawl for holding the slide 90 in its shifted position, an actuating member on the slide arranged to engage the switch cam to shift the switch cam after the slide has been moved a predetermined distance, a holding pawl releasing device, a member arranged to be engaged by the switch cam adapted to engage the releasing device to free the holding pawl, and means on the releasing device for engaging the first mentioned pawl to move it out of engagement with the rack when the holding pawl is released, and means to return the slide to its initial position, substantially as described.

95 29. A controlling device for printing members of a printing machine, comprising a rotary drum, a plurality of shiftable selectors thereon, a plurality of electric switches surrounding said drum having actuating projections extending in the lines of movement 100 of projections on the selectors, a switch cam normally held in one position and arranged to move the selectors in the path of the projections on one set of switches, and an actuating device for said switch cam arranged 105 to move the switch cam at predetermined intervals to throw one or more of the selector projections in the path of the projections on the other switches, substantially as described.

110 30. A printing machine having a plurality of printing blocks for printing the field, a plurality of printing blocks for printing the border, means for raising and lowering the printing blocks, an electrical controlled 115 latch for each of the printing blocks arranged to prevent the printing blocks from falling on the fabric beneath them, means for feeding the fabric to be printed below the printing blocks, a rotatable drum, each 120 125 130

latch having a switch, said switches surrounding the drum, an actuating lever for each switch, the actuating levers for the switches for the border blocks lying in one path while the actuating levers for the switches controlling the field blocks lying in another path, shiftable selectors on said drum, each selector representing a section of the fabric passing beneath the printing blocks, gearing connecting the drum and printing machine to move them in timed relation to each other, said selectors having projections thereon arranged to actuate the

switches, and a switch cam normally held in one position to move the projections on the 15 selectors in the path of one set of switches, and means for periodically shifting the switch cam to move one or more selectors so that the actuating projections thereon will actuate the other switches, substantially as 23 described.

In testimony whereof, we have hereunto set our hands.

A. JONES.

HARRY A. WEBSTER.
